(57) CLAIM

The ornamental design for a bottle, as shown and described.

DESCRIPTION

FIG. 1 is a top perspective view of a first embodiment of a bottle, showing my new design.

FIG. 2 is a partially enlarged view thereof, taken from FIG. 1.

FIG. 3 is a front view thereof.

FIG. 4 is a rear view thereof.

FIG. 5 is a first side view thereof.

FIG. 6 is a second side view thereof.

FIG. 7 is a top view thereof.

FIG. 8 is a bottom view thereof.

FIG. 9 is an exploded top perspective view thereof.

FIG. 10 is an exploded front view thereof.

FIG. 11 is a cross-sectional view thereof, taken along line 11-11 in FIG. 1.

FIG. 12 is a top perspective view of a second embodiment of a bottle, showing my new design.

FIG. 13 is a partially enlarged view thereof, taken from FIG. 12.

FIG. 14 is a front view thereof.

FIG. 15 is a rear view thereof.

FIG. 16 is a first side view thereof.

FIG. 17 is a second side view thereof.

FIG. 18 is a top view thereof.

FIG. 19 is a bottom view thereof.

FIG. 20 is an exploded top perspective view thereof.

FIG. 21 is an exploded front view thereof.

FIG. 22 is a cross-sectional view thereof, taken along line 22-22 in FIG. 12.

FIG. 23 is a top perspective view of a third embodiment of a bottle, showing my new design.

FIG. 24 is a partially enlarged view thereof, taken from FIG. 23.

FIG. 25 is a front view thereof.

FIG. 26 is a rear view thereof.

FIG. 27 is a first side view thereof.

FIG. 28 is a second side view thereof.

FIG. 29 is a top view thereof.

FIG. 30 is a bottom view thereof.

FIG. 31 is an exploded top perspective view thereof.

FIG. 32 is an exploded front view thereof; and,

FIG. 33 is a cross-sectional view thereof, taken along line 33-33 in FIG. 23.

The bottle has been shown with symbolic breaks in FIGS. 12, 14-17, and 20-22. The appearance of any portion of the article between the break lines forms no part of the claimed design.

The broken lines in the figures illustrate the portions of the bottle that form no part of the claimed design.
